UNITED STATES PATENT OFFICE

2,291,363

REFRIGERANT EVAPORATOR

Leonard W. Atchison, Schenectady, N. Y., assignor
to General Electric Company, a corporation of
New York

Application August 1, 1941, Serial No. 404,963

9 Claims. (Cl. 62—126)

My invention relates to refrigerant evaporators and particularly to such evaporators having continuous vaporizing conduits supplied by expansion devices of the fixed restricted opening type.

Evaporators of a continuous or series coil type tend to accumulate liquid in the lower portions of the coil during the inactive periods of the cycle of operation of the refrigerating machine. The cooled liquid may form slugs which pass to the compressor when the machine is restarted and it is necessary to provide some arrangement for trapping the slugs and preventing their reaching the compressor where they might cause damage. When a capillary tube or other expansion device of the fixed restricted opening type is employed, a considerable quantity of liquid refrigerant may be collected in the condenser or liquid receiver at the time the compressor is stopped and this liquid refrigerant will continue to flow to the evaporator and a large proportion of this liquid may flow to the trap at the end of the evaporator and be collected therein. When the machine is restarted a substantial period of time is necessary before the flow of liquid refrigerant from the condenser is adequate to wet the entire interior surface of the evaporator coil, and a considerable portion of the coil, therefore, may have no liquid refrigerant in it which is available for immediate refrigeration when the compressor is started. Accordingly it is an object of my invention to provide a refrigerant evaporator of the continuous coil type including an improved arrangement for assuring the presence of liquid refrigerant in a substantial portion of the evaporator as soon as the operation of the compressor is resumed after an inactive period during the refrigeration cycle.

Another object of my invention is to provide a refrigerant evaporator including a liquid vaporizing portion and a liquid and gas separating header and an improved arrangement for preventing the flow of liquid refrigerant from the header into the suction line during the inactive period when the compressor is stopped during the refrigeration cycle.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a side elevation partly in 55

section of a household refrigerator provided with a refrigerating machine including an evaporator embodying my invention; Fig. 2 is an enlarged perspective rear view of the evaporator shown in Fig. 1; Fig. 3 is an enlarged sectional side elevation of the header in the side wall of the evaporator shown in Figs. 1 and 2; and Fig. 4 is an enlarged side elevation of the outlet header of the evaporator shown in Figs. 1 and 2.

The evaporator shown in the drawing comprises generally a sheet metal structure providing the side and bottom walls of a freezing compartment and having arranged therein two continuous refrigerant vaporizing conduits connected in series by an intermediate header, the first conduit being supplied with refrigerant from a capillary tube expansion device and refrigerant being withdrawn from the other conduit and entering a second header. A refrigerated shelf is provided which is cooled by a flooded conduit communicating at both ends with the second header and vaporized refrigerant is withdrawn from the evaporator by a suction line which opens in communication with the upper portion of the second header. The intermediate header serves as a liquid trap between the two conduits, the second conduit being provided with a gooseneck or bowed portion extending downwardly within the header and having its open end communicating with the upper portion of the header. A restricted aperture in the bottom of the bowed portion near the bottom of the header is employed to meter liquid refrigerant from the header into the second conduit and another restricted opening is provided at the end of the bowed portion near the outlet of the header at about the same level as the open end of the bowed portion so that during the inactive period of the refrigeration cycle the pressures in the two conduits will be substantially equalized and liquid refrigerant will be trapped in the intermediate header. The suction line is provided with a similar bowed portion in the second header. This bowed portion is also provided with two restricted apertures in similar positions to those in the bowed portion of the conduit in the intermediate header. However the restricted opening for metering liquid refrigerant into the suction line is arranged at or near the normal level of liquid refrigerant in the second header rather than at the bottom of the header. During the "off" period of the refrigeration cycle liquid refrigerant which continues to flow from the condenser and through the capillary tube will pass through the first conduit into the intermediate header where it will

be trapped, since the pressure in the header and in the second conduit is substantially equalized so that only a small flow of gaseous refrigerant continues through the upper restricted aperture. When the refrigerating machine is again started the liquid refrigerant in the intermediate header flows into the second conduit and, thus, is immediately available to produce refrigeration in a substantial portion of the evaporator.

Referring now to the drawing, in Fig. 1 I have shown a household refrigerator comprising an insulated cabinet 10 having a door 11 and a food compartment 12. The food compartment is cooled by an evaporator or vaporizing unit 13 connected in the refrigerant circuit of a refrigerating machine comprising a hermetically sealed motor-compressor unit 14 and an air cooled condenser 15 mounted on the back of the cabinet 10. The compressor unit 14 is mounted in a machinery compartment below the food compartment 12 and insulated therefrom by a bottom wall of the compartment 12 (not shown). During the operation of the refrigerating machine liquid refrigerant within the evaporator 13 absorbs heat from the compartment 12 and is vaporized and the vapor is withdrawn from the evaporator through a suction line 16 by operation of the compressor in the unit 14. The compressor compresses the withdrawn vaporized refrigerant and discharges it through a connection 17 to the condenser 15. The hot compressed refrigerant is cooled and liquefied in the condenser by the natural circulation of air over the outside surface thereof. The liquid refrigerant is delivered to the evaporator through a capillary tube 18, the major portion of which is secured to the suction line in heat exchange relation therewith. The capillary tube maintains a predetermined pressure difference between the condenser and evaporator and determines the rate of flow of the refrigerant. When the operation of the compressor in the unit 14 is stopped, any liquid refrigerant remaining in the condenser will continue to flow to the evaporator through the capillary tube until pressure equilibrium is reached.

The construction and arrangement of the evaporator 13 is clearly shown in Fig. 2. The evaporator comprises a rectangular metal sheet 19 bent into U-shaped form and provided with flanges 20 and 21 for securing the evaporator to the top plate or inner liner of the refrigerator cabinet. On the sheet 19 are provided a section of conduit 22 and a section of conduit 23 connected in series by a header 24 to form a continuous refrigerant vaporizing passage. The conduits and the header are formed in any suitable manner and are arranged in good heat exchange relationship with the sheet 19 and preferably are secured to or formed on the sheet while it is flat and are then bent with the sheet to form the U-shaped evaporator as shown. The conduit 22 is arranged adjacent the edges of the sheet 19 and the conduit 23 extends back and forth across the sheet within the area enclosed by the conduit 22. Liquid refrigerant from the capillary tube 18 enters the conduit 22 and flows around the edges of the sheet and thence into the upper portion of the header 24. From the header 24 the refrigerant flows into the conduit 23 and thence back and forth from one wall of the evaporator to the other across the bottom wall and thence into the top of a header 25 which extends across the back of the evaporator at the top thereof and is secured to the side walls by flanges 26 and 27. A shelf 28 is secured to the

side walls by flanges 29 and 30 and extends across the freezing compartment formed by the sheet 19 about midway between the top and bottom thereof. The shelf is cooled by sinuous conduit 31 having its ends 32 and 33 opening into the bottom of the header 25 below the level of liquid refrigerant therein so that the conduit 31 is maintained flooded with liquid refrigerant. Refrigerant vaporized in the evaporator is withdrawn from the header 25 through the suction line 16. The U-shaped portions of the conduits 22 and 23 tend to trap liquid refrigerant in their lower portion during the "off" period of the refrigerating cycle. However with the continued admission of the refrigerant to the evaporator during the "off" period liquid refrigerant tends to flow out of the conduits so that when the operation of the compressor is resumed substantial portions of the conduits are dry and are not supplied with liquid refrigerant until sufficient liquid has been condensed to flow over and wet all the dry areas of the evaporator. Uneven refrigeration of the walls of the evaporator may therefore result. In order to provide refrigeration throughout the conduit 23 when operation of the compressor is resumed, I construct the header 24 so that it acts as a liquid trap during the "off" period of the cycle and so that it supplies liquid refrigerant to the conduit 23 as soon as the compressor is started. As shown in Fig. 3, the conduit 23 is provided with a bowed extension or gooseneck 34 forming a portion of the conduit within the header 24. The extension 34 has its open end 35 in direct communication with the upper portion of the header 24 and the lowermost portion of the extension lies at the bottom of the header 24. Conduit 23 constitutes a suction line with respect to the first portion of the evaporator comprising the conduit 22 and the header 24 and during the normal withdrawal of refrigerant from the header 24 gaseous refrigerant flows from the header through the opening 35 and liquid refrigerant flows through a restricted aperture 36 near the bottom of the bowed portion which meters the flow of liquid refrigerant. A small amount of gaseous refrigerant also enters the conduit 23 through a restricted opening 37 in the upper portion of the extension 34 at about the same level as the open end thereof. A continuous supply of liquid and vaporized refrigerant is therefore admitted to the conduit 23 during the active portion of the refrigerating cycle. When the withdrawal of vaporized refrigerant is stopped by the stopping of the compressor the pressures in the header 24 and in the conduit 23 are substantially equalized by the flow of vaporized refrigerant through the restricted opening 37. Liquid refrigerant, which continues to enter the header 24 from the conduit 22 because of the continued supply of liquid refrigerant through the capillary tube 18, collects in the header 24, extension 34 filling with liquid refrigerant to the level of the liquid refrigerant in the header. As soon as the operation of the compressor is resumed the pressure in the conduit 23 is lowered and the normal pressure difference is restored so that the liquid refrigerant in the bowed extension 34 flows to the conduit 23 and the remainder of the liquid in the header 24 continues to flow through aperture 36 and supply liquid refrigerant to the conduit 23. This provides a supply of liquid refrigerant for the conduit 23 for a considerable period of time before sufficient liquid refrigerant is supplied through the capillary tube 18

to reach the conduit 23. Active refrigeration is therefore obtained in the conduit 23 much sooner than would be possible if it were necessary to wait until an adequate supply was available from the capillary tube. The liquid and gaseous refrigerant separate in the header 25 and the vaporized refrigerant is withdrawn from the header through the suction line 16. In order to provide a quiet zone of liquid refrigerant within the header 25 and prevents slugs of liquid from entering the suction line, two baffles 38 and 39 are provided between the ends 32 and 33, respectively, of the conduit 31 and the suction line 16. Baffles 38 and 39 do not extend entirely across the header 25 but provide communication between the ends and the central portion of the header both above and below the normal level of liquid refrigerant. The suction line 16 is provided with a bowed extension or gooseneck 40 within the central portion of the header 25, the open end of the extension communicating with the top central portion of the header. A restricted orifice 42 is provided in the extension 41 in order that small amounts of liquid may be metered from the header into the suction line. This is necessary in order that oil or other lubricant which is unavoidably entrained in the refrigerant discharged from the compressor may be returned to the compressor. If the lubricant and liquid refrigerant separate by gravity only oil from the surface of the liquid in the header need be removed through the orifice 42; however, if the lubricant is intimately mixed or dissolved in the liquid refrigerant, it is necessary to withdraw small amounts of the mixture of liquid refrigerant and lubricant and to separate the lubricant from the liquid refrigerant before the mixture reaches the compressor. This separation is accomplished in the heat exchanger since the liquid mixture will absorb heat from the hot liquid in the capillary tube, which is in heat exchange with the suction line, and the liquid refrigerant will thereby be vaporized leaving the oil which is carried with the vaporized refrigerant to the compressor. The extension 40 is also provided with a restricted aperture 43 which operates to equalize pressures in the same manner as the aperture 37 in the extension 34 in the header 24, thereby preventing the flow of quantities of liquid into the suction line during the inactive period of the refrigeration cycle.

During the operation of the refrigerating machine described above the conduit sections 22 and 23 act as a continuous refrigerant conduit during the active portion of the refrigerating cycle. Liquid and gaseous refrigerant, flowing continuously through the section 22 and into the section 23 and thence to the header 25; and the conduit 31 in the shelf 28, is maintained flooded with liquid refrigerant since the header 25 is normally about half filled with liquid refrigerant. During the "off" period of the cycle liquid refrigerant collects in the header 24, and, even if all the liquid refrigerant should flow from the conduit 22 into the header and no more liquid be supplied to the conduit 22, nevertheless, there will be available a substantial quantity of liquid refrigerant for supplying refrigeration in conduit 23 as soon as the compressor is again started. The arrangement of the extension 40 of the suction line 16 prevents the flow of liquid refrigerant to the suction line 16 even though an abnormal quantity of liquid refrigerant should enter the header 25 during the "off" period of the cycle. Furthermore the aperture 42 in the ex-

tension 40 provides for the return of a metered quantity of liquid to the suction line so that lubricating oil may be returned to the compressor.

While I have shown a particular embodiment of my invention in connection with a household refrigerator, other applications will readily be apparent to those skilled in the art. I do not therefore desire my invention to be limited to the particular construction shown and described and I intend in the appended claims to cover all modifications within the spirit and scope of my invention.

What I claim as new and desire to secure by Letters Patent of the United States is:

1. An evaporator for a refrigerating machine comprising a liquid vaporizing section and a header in communication therewith, a connection for admitting liquid refrigerant to said vaporizing section, and a suction conduit entering said header and opening into the upper portion thereof and having a portion extending downwardly in said header, said conduit having two restricted apertures therein the first at substantially the same level as the open end of said conduit and the second adjacent the lowermost part of said downwardly extending portion, said restricted apertures being so located that liquid refrigerant is metered into said suction conduit through said second aperture during the normal withdrawal of vaporized refrigerant and so that the pressures of vaporized refrigerant within said header and within said suction conduit are substantially equalized through said first aperture regardless of the accumulation of liquid refrigerant in said header during the inactive period when vaporized refrigerant is not being withdrawn from the evaporator.

2. An evaporator for a refrigerating machine comprising a liquid vaporizing section and a header in communication therewith, a connection for admitting liquid refrigerant to said vaporizing section and a suction conduit entering said header and opening into the upper portion thereof and having a bowed portion extending downwardly in said header, the lowermost part of said bowed portion being arranged adjacent the bottom of said header, said conduit having two restricted apertures therein the first at substantially the same level as the open end of said conduit and the second in said lowermost part of said bowed portion, said restricted apertures being so located that liquid refrigerant is metered into said suction conduit through said second aperture during the normal withdrawal of vaporized refrigerant and so that the pressures of vaporized refrigerant within said header and within said suction conduit are substantially equalized through said first aperture regardless of the accumulation of liquid refrigerant in said header during the inactive period when vaporized refrigerant is not being withdrawn from the evaporator.

3. An evaporator for a refrigerating machine comprising a liquid vaporizing conduit and a header in communication therewith, an expansion device of the fixed opening type for admitting liquid refrigerant to said conduit, said conduit being arranged in series between said expansion device and said header, and a suction conduit entering said header and opening into the upper portion thereof and having a bowed portion extending downwardly in said header, the lowermost part of said bowed portion being arranged adjacent the bottom of said header, said suction

conduit having two restricted apertures therein the first at substantially the same level as the open end of said conduit and the second in said lowermost part of said bowed portion, said restricted apertures being so located that liquid refrigerant is metered into said suction conduit through said second aperture during the normal withdrawal of vaporized refrigerant and so that the pressures of vaporized refrigerant within said header and within said suction conduit are substantially equalized through said first aperture regardless of the accumulation of liquid refrigerant in said header during the inactive period when vaporized refrigerant is not being withdrawn from the evaporator.

4. An evaporator for a refrigerating machine comprising a liquid vaporizing section and a header in communication therewith, a connection for admitting liquid refrigerant to said vaporizing section, a suction connection entering said header and opening into the upper portion thereof and having a portion extending downwardly in said header, said connection having two restricted apertures therein the first at substantially the same level as the open end of said connection and the second adjacent the lowermost part of said downwardly extending portion, said restricted apertures being so located that liquid refrigerant is metered into said suction connection through said second aperture during the normal withdrawal of vaporized refrigerant and so that the pressures of vaporized refrigerant within said header and within said suction connection are substantially equalized through said first-aperture regardless of the accumulation of liquid refrigerant in said header during the inactive period when vaporized refrigerant is not being withdrawn from the evaporator, a suction conduit for removing vaporized refrigerant from said evaporator and a second vaporizing conduit connected in series between said suction connection and said suction conduit for vaporizing liquid refrigerant withdrawn from said header.

5. An evaporator for a refrigerating machine comprising a liquid vaporizing section and a header in communication therewith, a connection for admitting liquid refrigerant to said vaporizing section, a suction connection entering said header and opening into the upper portion thereof and having a portion extending downwardly in said header, said connection having two restricted apertures therein the first at substantially the same level as the open end of said connection and the second adjacent the lowermost part of said downwardly extending portion said restricted apertures being so located that liquid refrigerant is metered into said suction connection through said second aperture during the normal withdrawal of vaporized refrigerant and so that the pressures of vaporized refrigerant within said header and within said suction connection are substantially equalized through said first aperture regardless of the accumulation of liquid refrigerant in said header during the inactive period when vaporized refrigerant is not being withdrawn from the evaporator, a second vaporizing conduit connected to receive refrigerant from said suction connection and having a second header at its outlet end for separating liquid and vaporized refrigerant, a suction conduit for removing vaporized refrigerant from said second header and having a bowed portion extending downwardly within said second header and provided with restricted apertures similar

to those in said suction connection for preventing the flow of liquid from said second header except during the normal withdrawal of vaporized refrigerant through said suction conduit and for 5 metering the flow of liquid from said second header to said suction conduit during the normal withdrawal of vaporized refrigerant.

6. An evaporator for a refrigerating machine comprising a liquid vaporizing conduit divided in 10 two sections and having a header connecting the sections, a connection for admitting liquid refrigerant to the first of said sections, the second of said sections entering said header and opening into the upper portion thereof and having a portion 15 extending downwardly in said header, said portion of said second section having two restricted apertures therein the first at substantially the same level as the open end of said section within said header and the second adjacent 20 the lowermost part of said downwardly extending portion, and a suction connection for removing vaporized refrigerant from the said second section of said conduit, said restricted apertures being so located that liquid refrigerant is metered 25 into said second section through said second aperture during the normal withdrawal of vaporized refrigerant from the evaporator and so that the pressures of vaporized refrigerant within said header and within said second section of said conduit are substantially equalized through said 30 first aperture regardless of the accumulation of liquid refrigerant in said header during the inactive period when vaporized refrigerant is not being withdrawn from the evaporator, said header constituting a liquid trap and providing a supply of liquid refrigerant for said second section of said conduit immediately when normal withdrawal of vaporized refrigerant is resumed.

7. An evaporator for a refrigerating machine 40 comprising a sheet metal wall structure and means providing two extended refrigerant conduits arranged on the surface of said structure, a connection for admitting liquid refrigerant to one of said conduits, a connection for removing 45 vaporized refrigerant from the other of said conduits and a header connecting said conduits in series, said other of said conduits having a portion entering said header and opening into the upper portion thereof, said portion of said other 50 conduit being bowed downwardly within said header and having two restricted apertures therein the first at substantially the same level as the open end of said portion of said other conduit and the second adjacent the lowermost part 55 of said bowed portion, said restricted apertures being so located that liquid refrigerant is metered into said other conduit through said second aperture during the normal withdrawal of vaporized refrigerant from said evaporator and 60 so that the pressures of vaporized refrigerant within said header and within said other conduit are substantially equalized through said first aperture regardless of the accumulation of liquid refrigerant in said header during the inactive 65 period when vaporized refrigerant is not being withdrawn from the evaporator.

8. An evaporator for a refrigerating machine comprising a rectangular sheet metal structure having two sections of a refrigerant vaporizing 70 conduit arranged thereon, one of said sections of conduit extending around the border of said sheet metal structure and the other of said sections extending back and forth across the face of said sheet metal structure in the area within

said one section of conduit, a header connecting said sections of conduit in series, a connection for admitting liquid refrigerant to one of said sections, a connection for withdrawing vaporized refrigerant from the other of said sections, said other of said sections having an end opening into the upper portion of said header, and having a bowed portion extending downwardly within said header, said bowed portion having two restricted apertures thereon the first at substantially the same level as the open end of said section and the second adjacent the lowermost part of said bowed portion, said restricted apertures being so located that liquid refrigerant is metered into said other section of conduit through said second aperture during the normal withdrawal of vaporized refrigerant and so that the pressures of vaporized refrigerant within said header and within said other section of conduit are substantially equalized through said first aperture regardless of the accumulation of liquid refrigerant in said header during the inactive period when vaporized refrigerant is not being withdrawn from the evaporator.

9. An evaporator for a refrigerating machine comprising a rectangular sheet metal structure having two sections of a refrigerant vaporizing conduit arranged thereon, one of said sections of conduit extending around the border of said sheet metal structure and the other of said sections extending back and forth across the face of said sheet metal structure in the area within

said one section of conduit, an elongated header arranged near one end of said sheet and substantially parallel to said one end connecting said sections of conduit in series, a connection for admitting liquid refrigerant to one of said sections, a connection for withdrawing vaporized refrigerant from the other of said sections, said other of said sections having an end opening into the upper portion of said header and having a bowed portion extending downwardly with said header, said bowed portion having two restricted apertures thereon the first at substantially the same level as the open end of said section and the second adjacent the lowermost part of said bowed portion, said restricted apertures being so located that liquid refrigerant is metered into said other section of conduit through said second aperture during the normal withdrawal of vaporized refrigerant and so that the pressures of vaporized refrigerant within said header and within said other section of conduit are substantially equalized through said first aperture regardless of the accumulation of liquid refrigerant in said header during the inactive period when vaporized refrigerant is not being withdrawn from the evaporator, said sheet metal structure being bent in U-shaped form to provide two side walls and a bottom wall, said header being arranged near the top of one of said side walls.

LEONARD W. ATCHISON.
